(57) **CLAIM**

The ornamental design for a video doorbell, as shown and described.

DESCRIPTION

FIG. 1 is a top, front, right side perspective view of a video doorbell showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The dashed broken lines in the drawings represent unclaimed portions of the design, and the dash-dot broken lines represent boundaries of the claimed design. All of the broken lines form no part of the claimed design.

1 Claim, 7 Drawing Sheets

FIG. 1

FIG. 2

FIG. 3

FIG. 4

FIG. 5

FIG. 6

FIG. 7
